His ATTORNEY.

UNITED STATES PATENT OFFICE

JOHN W. LIVINGSTON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRACK BRAKE

Application filed April 17, 1931. Serial No. 530,794.

My invention relates to railway track brakes, that is, to devices which are located in the trackway for coaction with the wheels of passing cars in order to retard the motion of such cars. More specifically, the present invention relates to track brakes of the eddy current type, and has for an object the provision of a brake of this type wherein the brake shoes automatically move downwardly at the same time that they move away from the positions wherein they engage the car wheels.

I will describe one form of brake embodying my invention, and will then point out the novel features thereof in the claim.

In the accompanying drawing, Fig. 1 is a transverse sectional view showing one form of brake embodying my invention, with the parts in the positions which they occupy when the operating magnet is deenergized. Fig. 2 is a view showing the brake of Fig. 1 with the parts in the positions which they occupy when the operating magnet is energized.

Similar reference characters refer to similar parts in each of the views.

Referring to the drawing, the reference character R designates a track rail. Associated with this rail is a U-shaped electromagnet M, comprising a bar 2 of magnetizable material located beneath the rail and disposed transversely with respect thereto. The two legs of the magnet M are designated 4^a and 4^b, respectively, and these legs project upwardly from the bar 2 on the opposite sides of the rail R. Each leg is formed of thin laminations which are parallel to the rail, and which are biased to bend away from the rail into the positions in which they are shown in Fig. 1. These legs may be assembled in the manner shown and described in United States Letters Patent No. 1,846,831, granted to Basel & Meyer on Feb. 23, 1932, and each leg may be biased to the open position shown in Fig. 1 by a spring (not shown) attached to the leg and to the foundation on which the apparatus is mounted. Coacting with the two legs 4^a and 4^b are two pole shoes 5^a and 5^b, respectively, which shoes are hinged at 7^a and 7^b, respectively, to the

inner edges of the upper surfaces of the magnet legs. Each pole shoe has a portion which extends outwardly from the hinge to coact with the top of the associated magnet leg, and another portion which extends inwardly from the hinge toward the track rail. The latter portion is provided with the usual brake shoe 6^a or 6^b for coaction with the sides of a wheel on the track rail R. Each pole shoe is biased as by gravity so that when the electromagnet is deenergized, the outwardly extending portion swings upwardly away from the associated leg, and the inwardly extending portion swings downwardly. The magnet is provided with the usual operating winding 3, which may be supplied with current in order to energize the device.

When the magnet M is deenergized, the parts assume the positions in which they are shown in Fig. 1. The laminated legs 4^a and 4^b are bent away from the rail R, and the pole shoes 5^a and 5^b are swung away from the upper surfaces of these legs. The brake shoes 6^a and 6^b are then out of the path of any portion of a car or locomotive traveling on the rail R. When the magnet becomes energized, the parts move to the positions in which they are shown in Fig. 2, owing to the tendency of the movable parts to reduce the reluctance of the magnetic circuit. In these positions, the laminated legs are bent toward the track rail and the pole shoes are so swung that their outwardly projecting portions rest on the upper surfaces of the legs. The brake shoes 6^a and 6^b are then in the proper positions to coact with the two sides of a wheel traveling on the track R.

One advantage of a brake shoe embodying my invention, is that it eliminates the necessity for any auxiliary mechanism for raising and lowering the brake shoes.

Although I have herein shown and described only one form of track brake embodying my invention, it is understood that various changes and modifications may be made therein within the scope of the appended claim without departing from the spirit and scope of my invention.

Having thus described my invention, what I claim is:

A railway track brake comprising a U-shaped electromagnet located in the track-way with its legs on opposite sides of a rail, such legs being formed of laminations which are parallel to the rail and are biased to bend away from the rail, and pole shoes hinged to the inner edges of the upper surfaces of said legs, each pole shoe having a

portion which extends outwardly from the hinge to coact with the top of the associated leg and another portion which extends inwardly from the hinge to coact with a wheel on the rail, and each pole shoe being biased so that its outwardly extending portion swings upwardly away from the associated leg when the magnet is deenergized.
